Robert Holmes

United States Patent Office.

ROBERT HOLMES, OF DETROIT, MICHIGAN.

Letters Patent No. 76,326, dated April 7, 1868.

IMPROVEMENT IN BASE-BURNING STOVES.

The Schedule referred to in these Letters Patent and making part of the same.

Know all men that I, ROBERT HOLMES, of Detroit, in the county of Wayne, and State of Michigan, have invented a new and useful Improvement on Apparatus for Burning Coal, and consuming the smoke and gases thereof; and I do declare that the following is a true and accurate description thereof, reference being had to the accompanying drawings, and to the letters of reference marked thereon, and being a part of this specification.

The object of this invention is so to construct an apparatus for the burning of anthracite and bituminous coals that it will also consume all the smoke and gases thrown off by the combustion of the coal. This is done by having the draught pass downward through the fire, conveying the smoke and gases into the base, to which a supply of oxygen or common air is admitted, through the proper orifices in the cap of the base, around and on the outer sides of the fire-basket. This base must be kept perfectly tight, so that no air can enter it, except through the orifices above referred to. In this way, the oxygen of the common air is mixed with the carbon of the smoke and gases, and, being ignited by the fire in the basket, they are entirely consumed. The apparatus also contains a magazine, for the purpose of holding a supply of coal, which feeds the fire in the basket in the same manner as in the ordinary base-burning stoves for burning anthracite coal.

The use of bituminous coal has been attended with many objections heretofore, arising principally from the large amount of unconsumed carbon thrown off in the form of smoke and gases, and the frequency with which the coal must be supplied. In my invention, I obviate these serious objections, as I entirely consume this carbon, thereby deriving a much greater heat from the same amount of coal, and consequently requiring a less quantity of fuel to heat a given space.

My invention is applicable to all kinds of heating or cooking-stoves, hot-air furnaces, stationary or locomotive-boilers.

The drawing, which is a vertical sectional view of my invention, shows it applied to a hot-air furnace, in which A represents the base; B, the fire-basket; C, the magazine; D, the entrance for the draught; E, the damper; F, the cover to the magazine, and the place for filling in the coal. G is the semi-rotating grate or bottom of the fire-basket, operated by the rod H, which projects, with a proper handle, through the front of the base. I is a proper door, opening in the front of the base, through which to take out ashes. J are the orifices for the admission of air to the base.

To kindle a fire, fill the fire-basket up to the bottom of the draught D. Then lay the kindling on to the coal and ignite it, taking care to leave the damper E open. The draught, being downward and through the fire, carries all the smoke and gases down into the base, while the air admitted to it through the openings J, mingling with them, causes them to burn. The course of the draught from the base is upwards, through the flues L, into the drum M, and thence into the flue P and the chimney. N are radiating-flues.

When it is required to clear the base from ashes, close the damper E, and open the damper K, when a direct draught is obtained, through the pipe or flue O, by opening the door I, through which the refuse can be taken out.

What I claim as my invention, and desire to secure by Letters Patent, is—

The combination and arrangement of the dampers E, I, and K, and flues D, O, L, and P, to produce either a downward or a direct draught, substantially as described.

ROBERT HOLMES.
